DESIGN FOR AN ELECTRICAL CONNECTOR PLUG

Tom Moore Urell, Tioga, Pa.

Application May 27, 1943, Serial No. 110,305

Term of patent 14 years

To all whom it may concern:

Be it known that I, Tom Moore Urell, a citizen of the United States of America, residing at Tioga, in the county of Tioga and State of Pennsylvania, United States of America, have invented a new, original, and ornamental Design for Electrical Connector Plugs, of which the following is a specification, reference being had to the accompanying drawing, forming part thereof.

I claim:

The ornamental design for an electrical connector plug, as shown.

TOM MOORE URELL.
